Des. 220,742
Patented May 18, 1971

220,742

SWIM SUIT OR SIMILAR ARTICLE

Edward H. Mohl, 5716 Woodbine Ave.,
Philadelphia, Pa. 19131

Original design application Nov. 25, 1968, Ser. No. 14,642, now Patent No. 216,245, dated Dec. 9, 1969. Divided and this application July 24, 1969, Ser. No. 19,343

Term of patent 14 years

Int. Cl. D2—01

U.S. Cl. D2—42

Fig. 1

Fig. 2

FIG. 1 is a front elevational view of a swim suit or similar article showing my new design, the back thereof being conventional and unornamented; and

FIG. 2 is a division of design application Ser. No. 14,642, filed Nov. 25, 1968, now Pat. No. D. 216,245.

I claim:

The ornamental design for a swim suit or similar article, as shown and described.
